UNITED STATES PATENT OFFICE.

THOMAS J. YOUNG, OF NEW YORK, N. Y.

COMBINATION FURNITURE.

No. 882,772.

Specification of Letters Patent. Patented March 24, 1908.

Application filed June 3, 1907. Serial No. 376,935.

To all whom it may concern:

Be it known that I, THOMAS J. YOUNG, a citizen of the United States, residing in the borough of Brooklyn, county of Kings, city and State of New York, have invented an Improvement in Combination Furniture, of which the following is a specification.

My invention relates to an improvement in combination furniture and particularly to 10 a combined bed and couch or bed and chair, and the object thereof is the provision of a piece of furniture of the class to which this invention relates so constructed that the movable or convertible sections thereof are connected by suitable means, causing them to move simultaneously, the one being moved by the movement of the other and vice versa, to or from the interchangeable positions of the parts of the piece of furniture in making 20 thereof a bed or couch.

In carrying out my invention, I employ a suitable frame comprising end members, members connecting the end members, a suitable back section, a seat section preferably made similarly to the back section, means for pivotally mounting the back section in the frame, means for pivotally mounting the seat section in the frame and means connecting the said back and seat 25 sections to cause the same to move simultaneously with one another, as will be hereinafter more particularly set forth.

In the drawing, Figure 1 is a perspective view of my improved combined bed and couch, showing the same broken away centrally to economize space, and Fig. 2 is a transverse section showing the parts in a position, wherein the same are adapted to form 30 a bed.

Referring particularly to the drawing, in 40 constructing my improved combined bed and couch, I employ a frame preferably comprising similar end members *a* and *b*, which may be of any suitable design and made of any 45 desired material, and these end members *a* and *b* are joined by connecting members *c*, which as will be understood, may be of any desired length, depending of course upon whether the article of furniture is to be employed as a couch and bed or an easy chair 50 and bed, the length of the connecting members being comparatively short in the use of the article of furniture for the latter named purpose, whereas for the combined couch and bed, the connecting members *c* are necessarily of a length corresponding to that of the

average length bed, and moreover the frame structure may be strengthened by suitable cross straps *d* extending between and connected with the connecting members *c*, so as 60 to form a metal framework.

Together with the hereinbefore described frame structure, I employ a back section *e* and a seat section *f*, both of which are preferably constructed in a similar manner, which 65 is as follows:—In each of the sections *e*, *f*, I prefer to employ a central lattice work 10 of sheet metal strips or other similar material, in which at the crossing points of these strips, suitable double helico-volute springs are se- 70 cured at their central portions, these springs being secured to the lattice work by being wired thereto or being connected in any other suitable manner. As is customary, I also employ straps of burlap 12 or other 75 similar material passed over the springs 11 to secure their free ends in place. Moreover each of these back and seat sections *e*, *f* is advantageously provided with a skeleton which is suitably upholstered. The sections 80 *e*, *f* are pivotally mounted in the frames by trunnions.

The back section *e* is provided with trunnions *g* and the seat section *f* with similar trunnions *k* and these trunnions *g* and 85 *h* are received in suitable bearings provided therefor in the frame end members *a*, *b*. Within the frame end members *a*, *b* each trunnion *g* is provided with a sprocket *i* and similarly within the frame end members *a*, *b*, 90 each trunnion *h* is provided with a sprocket *k* and a chain *l* is passed around the pairs of sprockets *i* and *k* within each frame end member *a*, *b*. Only one set of sprockets and a chain are shown, but it is to be understood 95 that a corresponding set is located at the opposite side of the article of furniture. One of the trunnions *h* may be provided with a square stem extending through the frame end member *a* and adapted to receive the lever 13. 100

The seat section *f* is provided with bracket legs or supports *m* upon which the same rests when in the position shown in Fig. 2, these legs *m* resting against the face of the back section *e* when the article is in use as a 105 couch and in which the said back section *e* rests against suitable stops 14 provided in the frame end members *a*, *b* for this purpose.

On the inner faces of the frame end members *a*, *b*, I prefer to employ springs indicated at *n* and upon which the central part 110 of the seat section *f* bears when the article of

furniture is used as a seat or couch and upon which the central part of the back section *e* bears when the article is to be used as a bed, the function of these springs *n* being to cause 5 the parts to seat easily, that is without a jolt or jar in being converted from one position to the other and also to slightly assist in the initial return movement of the back and seat sections, the former of which as will be understood when the article is in use as a bed, 10 will be supported by the connecting members *c* and the cross straps *d*, whereas when in use as a couch, the seat section *f* is supported by the same parts.

15 It will be understood that the relative sizes of the sprockets *i* and *k* are such that in converting the hereinbefore described article of furniture from a couch to a bed, or vice versa, the seat section *f* will turn through an 20 angle of 180° , whereas the back section *e* will turn through an angle slightly greater than 90° and that by moving either the back or the seat section, the other section will be moved therewith; and it will be further understood that in lieu of the sprocket *i*, I may 25 employ a dummy wheel to which in the desired position, the chain *l* or other suitable connecting means is secured by a screw or otherwise.

30 I claim as my invention:

1. In a combined bed and couch and in combination, a frame, a seat section pivoted

forward in the frame, a back section pivoted at its lower end in the said frame, and devices connected to the said pivotal points and 35 also connected together for simultaneous action, whereby the seat section is turned over and outwardly and back section turned downwardly.

2. In a combined bed and couch and in 40 combination, end members, connecting members extending between and connected to said end members, a back section and a seat section, trunnions secured in the said back section, bearings to receive the same in the 45 said frame end members, trunnions secured in the said seat section, bearings to receive the same in the said frame end members, sprockets secured on the said trunnions within the frame end members and chains running over the said sprockets and operating within the said frame end members to cause the shifting of one of the said sections to effect the simultaneous shifting of the other section, the relation of the said sprockets being such that in shifting the seat section 50 through an angle of 180° effects a movement of the back section from its upright to its horizontal position and vice versa.

Signed by me this 27th day of May, 1907. 60
THOMAS J. YOUNG.
